MECHANISM FOR ACTUATING THE HEDDLE FRAMES IN LOOMS

Erwin Pfarrwaller, Winterthur, Switzerland, assignor to Sulzer Freres, Societe Anonyme, Winterthur, Switzerland, a corporation of Switzerland

Application May 20, 1952, Serial No. 288,919

16 Claims. (Cl. 139—58)

1

The present invention relates to a mechanism for actuating the heddle frames in a loom for weaving, more particularly to a mechanism which affords selective actuation of each heddle frame in different time relation to the weft thread insertions or picks and, if desired, to the action of the other heddle frames to produce different weave patterns. The mechanism according to the invention comprises cam elements and cam follower means positively actuating the heddle frames for changing the shed.

It is an object of the invention to provide a mechanism for actuating the heddle frames in a loom, which mechanism enables operation of the heddle frames according to a plurality of different weaving schedules and which comprises simple means for switching the operation from one schedule to another.

A further object of the invention resides in the provision of a mechanism for actuating the heddle frames in a loom according to a plurality of different operating schedules and comprising means for automatically switching operation of the heddle frames from one schedule to another.

An object of the invention is to provide a mechanism for actuating the heddle frames in a loom for weaving according to a variety of operating schedules, said mechanism comprising means for switching the mechanism from performing one schedule to performing a different schedule and means responsive to a predetermined number of performed picks and automatically actuating the switching means to change the weave pattern after a predetermined number of weft thread insertions.

The device according to the invention comprises two or more parallel shafts, each shaft carrying at least one set of cams, each set affording production of a binding of a binding schedule and comprising a cam element for each heddle frame needed for producing the desired weaving pattern which cam element positively actuates its heddle frame and is so curved as to move the heddle frame as required for the weaving pattern. The device also comprises means for selectively connecting the cam sets with cam followers, the latter forming part of a mechanism connected with and individually actuating a heddle frame.

In a preferred embodiment of the invention, there are a plurality of cam sets of different shape and/or speed provided for each heddle frame, and a cam follower means adapted to be selectively engaged by one of said cam sets. The

2

individual cam sets are arranged on different shafts and either the shafts or the cam follower means may be adapted to be moved so that the follower means are actuated either by a cam set on one shaft or by a cam set on another shaft.

In another embodiment of the invention, two shafts are provided, each carrying a plurality of axially displaceable cams which can be selectively brought to engage a cam follower means which is arranged between the two shafts and is movable towards one or the other shaft for selectively engaging the cams on one or the other shaft. This combination affords production of an increased number of weaving patterns.

There is, of course, one cam follower means for each heddle frame and a linkage between each follower means and frame to actuate the latter in accordance with the movements of the former which are caused by the cam by which it is engaged.

In a further embodiment, the cams are mounted on a rotatable frame in a circle coaxial with the frame, whereby, by rotation of the frame, one cam can be selected to engage a cam follower.

In all modifications the cams are rotated by the loom, and the part which is moved to effect engagement of a selected cam with the cam follower is temporarily connected with the loom drive to effect switching from one operating pattern to another.

The mechanism according to the invention is less complicated than conventional mechanisms employing perforated cards and the like. It has simple parts which are in positive engagement for actuating the harnesses. A loom equipped according to the invention can therefore be operated at higher speed than one which is controlled by jacquard and similar apparatuses. The mechanism according to the invention requires much less space than conventional harness controls. Cards of jacquard devices are very long for weaving patterns in which a binding is repeated often, whereas the cam sets forming part of the new mechanism take the same space, no matter whether they make one revolution or a great number of revolutions between changes of the binding.

With the new mechanism, the cam sets for effecting consecutive bindings which are used only once or a few times between changes can be prepared on a separate shaft without loss of time. Bindings which are consecutively used a great number of times can be effected by cam sets which are on the same shaft as the sets for

effecting the previous series of bindings because the time loss involved in that case by a single change is unimportant.

Further and other objects of the present invention will be hereinafter set forth in the accompanying specification and claims, and shown in the drawings which, by way of illustration, show what I now consider to be preferred embodiments of my invention.

In the drawings:

Fig. 1 is a diagrammatic layout of a shedding mechanism according to the invention;

Fig. 2 is a diagrammatic, part sectional, large scale view of a cam-controlled actuating device forming part of the mechanism shown in Fig. 1;

Fig. 3 is a cross-section taken along line III—III of Fig. 2;

Fig. 4 is a diagrammatic top view of a fabric showing a pattern produced by two harness frames;

Fig. 5 is a diagrammatic longitudinal sectional view of the fabric of Fig. 4;

Fig. 6 is a schematic, part sectional illustration of a mechanism according to the invention for the automatic operation of the device shown in Fig. 2;

Fig. 7 is a large-scale view of a detail of the mechanism shown in Fig. 6;

Fig. 8 is a cross-sectional view of a modification of a cam-controlled device for effecting shedding and producing more than two different bindings;

Fig. 9 is a top view of the device shown in Fig. 8;

Fig. 10 is a diagrammatic top view of a fabric showing a pattern produced by four harness frames;

Fig. 11 is a diagrammatic longitudinal sectional view of the fabric shown in Fig. 10;

Fig. 12 is a diagrammatic cross-sectional view of a further modification of a device for effecting shedding;

Fig. 13 is a diagrammatic plan view of a device of the type shown in Fig. 12;

Fig. 14 is a diagrammatic plan view of a modification of the device shown in Figs. 12 and 13;

Fig. 15 illustrates a detail of the device shown in Fig. 13.

Like parts are designated by like numerals in the different figures of the drawings.

Referring more particularly to Fig. 1, numeral 29 designates a motor driving the main shaft 23 of a loom by means of a transmission 21 and a main clutch 22. Shaft 23 drives shaft 25 of a picking mechanism 26 by means of gears 24. The picking mechanism for the shuttles which also includes means for connecting weft threads to the shuttles and other means for handling the weft threads if the shuttles are of the gripper type, is not illustrated because this does not form part of the present invention. Shaft 23 also operates a shuttle-receiving mechanism 27 by means of gears 28 and a shaft 29. Cams 30 are provided on shaft 23 for actuating a lay, not shown.

Clutch 22 can be disengaged by means of a lever 31 and a brake 33 is applied by lowering a lever 32 if the loom must be stopped.

Shaft 25 carries a chain wheel over which a chain 35 is laid which extends into a housing 34. Chain 35 drives a set of spur gear wheels 36, 37, 38 located in the housing 34. Wheel 38 is fast on a shaft 39 and wheel 36 on a shaft 40. Each of these shafts carries a plurality of cams. Motor 20 drives a shaft 42 through a speed-reducing transmission 20', shaft 42 driving a chain 43

70
75
80
85
90
95

through a claw clutch 41 and bevel gears 43'. Chain 43 rotates a shaft 45 in housing 34. Shaft 45 actuates a mechanism, to be described later, for selectively operating the shedding mechanism either by means of the cams on shaft 39 or on shaft 40. Numeral 51 designates a harness frame supported by vertically guided rods 50. The latter are linked individually to one arm of angular levers 49 by connecting links 50'. The other arm of levers 49 is pivoted to a horizontal rod 48 which is pivoted to one arm of a lever 47. The other arm of the latter is pivoted to an actuating rod 46.

For setting up a loom to produce a desired weaving pattern, a diagram of the required bindings is drawn showing the needed harness motions and threading of the heddles. In fabrics whose diagram shows only one type of binding this binding is repeated after inserting the number of weft threads which is also defined in the diagram. In a fabric whose diagram shows different bindings, the bindings follow according to a pattern defined in the diagram; individual bindings may be repeated as many times as prescribed by the diagram before a different binding is used. Different bindings are needed, for example, for producing borders or for repeatedly weaving individual cloth patterns in a continuous length of material which is afterwards cut to separate the individual pieces of cloth, for example, handkerchiefs, towels, and the like. A diagram for this purpose shows several different warp thread bindings, also the rapport, i. e. the number of weft insertions for each binding, and frequently a pattern for threading the heddles with warp threads. The diagram indicates the pick at which the warp threads determined by the warp rapport are in the upper or lower shed position. The harnesses must be controlled accordingly.

Figs. 2 and 3 show the mechanism for operating rod 46, which actuates a harness. Each of the parallel shafts 39 and 40 carries a set of cams. Each set produces a binding prescribed by the binding schedule of the desired weaving pattern and each set comprises a cam element for each individual harness needed for producing the desired weaving pattern. Each cam element consists of two cams and a cam follower is provided for each cam element which positively actuates a harness. The cams are so shaped as to produce the harness movement prescribed by the weaving pattern whenever the aforescribed diagram requires a change of the shed formed by the warp threads controlled by the particular harness before the next weft thread is inserted.

The cam sets and means following the cams thereof are selectively engaged by means of a special regulating device. Cam sets which produce different bindings which follow each other according to the weaving schedule are preferably arranged on different shafts in case several cam sets are carried by one shaft. This permits axial displacement of the cam set which is next to be used into a position opposite to the cam follower means before the binding is changed. In this case, the cam follower means can be made to engage the desired cam set without loss of time for producing the new binding.

The mechanism shown in Figs. 2 and 3 is built for actuating two harness frames and each shaft 39 and 40 carries a set of two cam elements, i. e. four cam discs 52 to 55 and 56 and 59, respectively, cams 54 and 55 not being visible in the drawing. Two two-arm levers swingable on shaft 70 are formed individually of two parallel plates 68, 68' and 69, 69' which are con-

nected by pins. Lever 68, 68' carries four cam follower rollers 60 to 63, and lever 69, 69' four cam follower rollers 64 to 67. Each lever plate has an upper extension, a pin 71 connecting the extensions of plates 68, 68' and pin 71' connecting the extensions of plate 69, 69'. The ends of rods 46 and 46' are swingable on pins 71 and 71', respectively. Shaft 70 supporting levers 68, 68' and 69, 69' extends between the prongs of a fork member 72 which swings about a shaft 13 which is made fast in housing 34. Two connecting rods 75 and 75' are swingably connected at one end with the fork member 72, projections 76 and 76' being provided for this purpose, and at their other ends with eccentrics 74 and 74' on shaft 45. In Fig. 2 only the mechanism for controlling rod 46 is visible.

Eccentric 74 is in its extreme left or in its extreme right position when the cam follower means 60 to 69 are in engagement either with a left or a right cam element. This blocks the device in engaged position against forces acting thereon from the harness actuating part of the mechanism.

Fig. 2 shows the levers 68 and 69 for the cam follower rollers in a position in which rollers 60 and 61 engage cam discs 52 and 53, respectively, and rollers 64 and 65 engage cam discs 54 and 55, the latter two not being visible. Fork member 72 is swung to its extreme left position. In this position, frames 51 and 51' actuated by rods 46, 46', respectively, are so operated as to produce the left portion of the pattern shown in Fig. 4. The binding-in of the weft threads follows the rule 1:1 up to weft thread *a*. The speed reduction between the main shaft 23 and shafts 39 and 40 is so chosen in combination with the configuration of the cams on discs 52 to 55 that the desired binding pattern is produced. The speeds of shafts 39 and 40 may be made different by replacing wheel 37 by a pair of spur gear wheels. If the mechanism is constructed as illustrated, the shed formed by the warp threads *b* and *c* is changed after each weft thread insertion. After insertion of weft thread *d*, the binding rule is changed to 2:2, whereby two consecutively inserted weft threads are bound by the warp threads. Binding 1:1 is restored at weft thread *e*, and, after insertion of weft thread *f*, the binding may again be changed to 2:2.

Since each cam disc 52 to 55 has two cams and each disc 56 to 59 has only one cam, shafts 39 and 40 can rotate at the same speed and yet produce two different bindings.

For producing pattern 2:2, after weft thread *d* is inserted, the cam elements 56 to 59 must be engaged and cam elements 52 to 55 disengaged. This is effected by depressing pedal 78 and pulling pawl 77 down (Fig. 1), so that spring 79 can push clutch part 44 to the right to engage part 41. Shaft 42 can now drive chain 43 which rotates shaft 45 and eccentric 74, causing rod 75 to pull fork lever 72 to the right. Gears 43' and the sprocket wheels for chain 43 are so constructed that shaft 45 is turned through 180° upon one revolution of shaft 42. Clutch 41, 44 is automatically disengaged after making a full turn, so that fork lever 72 stays in its right end position in which rollers 62, 63 and 66, 67 engage the cam discs 56 to 59.

If fork 72 and therefore the fulcrum 70 is in the extreme left position which is shown in Fig. 2, pin 71 moves along arc K₁ and rollers 60 and 61 abut against cams 52 and 53 in points 83 and

84, respectively, if the pin is in the middle between its extreme positions *h*₁ and *t*₁. If pin 71 is in position *h*₁, the harness frame connected therewith is in its top position, and, if pin 71 is in position *t*₁, the harness frame is in its bottom position. The shed is closed when pin 71 is in position *g*, i. e. in the middle between positions *h*₁ and *t*₁.

If fork 72 and therefore fulcrum 70 is in its extreme right position, pin 71 moves on arc K₂ between positions *h*₂ and *t*₂. Rollers 62, 63 engage the cam discs 56, 57 at points 85, 86 when the pin 71 is in the middle, *g*, between positions *h*₂ and *t*₂.

Line *m* connecting fulcrum 70 and the center of pin 71 is in the middle between points 83, 85 and 84, 86. Arcs K₁ and K₂ intersect in point *g* and are symmetric with respect thereto. Therefore the heddle frames 51 and 51' actuated by rods 46 and 46' go through like motions when the lever is in its left, as well as when it is in its right, position.

The geometry of the device may also be explained as follows: The axis *g* of the pivotal connection between lever 68 and rod 46 coincides with the line of intersection of two imaginary planes extending through the axis of the pivot 16 of lever 68 and through the middle between points 83 and 85 and 84 and 86 at which the cam follower rollers 60 to 63 engage different cam elements 52, 53 or 56, 57, one of said two planes corresponding to one extreme position of pivot 70 and the other plane corresponding to the other extreme position of pivot 70 when the cam elements 52, 53 and 56, 57 are in positions corresponding to the position of the heddle frame actuated thereby, in which the shed is in its middle position.

Clutch part 44 has a cam 80 which rests on pawl 77 if the clutch is disengaged as shown in Fig. 1. If pawl 77 is pulled down, part 44 moves to the right and engages clutch part 41 as shown in Fig. 6, which will be described later. In this position, pawl 77 is in the plane of cam 80. The latter extends around only a part of the circumference of part 44 and spring 81 can move pawl 77 so that its upper end is adjacent to the cylindrical surface of part 44, after the clutch has rotated through, say, 90°. After nearly a full revolution of the clutch, an inclined surface 82 on cam 80 contacts pawl 77 causing movement of part 44 to the left upon further rotation of the clutch and finally disengagement of the clutch, whereupon part 44 comes to a standstill in the position shown in Fig. 1.

In high-speed looms, the long time is very short between two consecutive picks, and there is little time for swinging fork lever 72 from one side to the other. If a number of heddle frames must be moved at the same time, the power required is so great that it is desirable to temporarily stop the loom by disengaging clutch 22.

In the embodiment of the invention illustrated in Figs. 1 to 3, switching of lever 72 is effected by the operator after a predetermined number of picks, which number is indicated to the operator by a conventional pick counter.

Fig. 6 illustrates a mechanism for automatic switching from one weave pattern to another. Shaft 23 drives a timing disc 92 by means of speed-reducing gears 91. Since shaft 23 makes one revolution per pick, the rotational speed of disc 92 is in proportion to the number of picks per time unit. This proportion can be changed by changing the speed-reducing gears 91. The

ratio of speed reduction must be integral. Cams 93 and 94 are secured by screws to disc 92. Upon rotation of disc 92 in the direction of arrow 96, one of the cams 93, 94 at a time presses lever 95 down against the action of spring 97 until the cam has passed a tooth 98 at the end of lever 95, i. e. until the cam and the tooth have reached the relative position shown for cam 93 in Fig. 6, whereupon lever 95 is pressed upward by spring 97. An air dash-pot 99 containing a piston 100 connecting with lever 95 and having a throttle 101 which may be made adjustable, dampens the movement of the lever. A small two-arm lever 102 is pivoted to the end of lever 95 whose outer arm 103 carries a small insulating plate 104. Lever 102 is resiliently held in a position longitudinally of lever 95 by a spring 109. If lever 95 moves upward to position B, arm 103, which is electrically conductive as is lever 95, abuts a stationary contact member 105, thereby closing an electric circuit 106 which includes a solenoid coil 107 whose armature 108 is connected with pawl 77 which is pulled down if coil 107 is energized. As seen in Fig. 7, arm 103 contacts member 105 only temporarily. As soon as lever 95 reaches its normal position C, lever 102 is pulled by spring 109 to its middle position in which circuit 106 is broken and solenoid 107 de-energized. For engaging clutch 41, 44, pawl 77 need be pulled down only momentarily. If lever 95 is depressed by the cams 93 or 94, switch 103, 105 is not closed because, if lever 95 reaches position D, insulation 104 is interposed between parts 103 and 105 and circuit 106 remains broken and solenoid 107 is not energized. Since plate 104 projects beyond the end of arm 103, it slides on contact member 105 upon movement of lever 95 to its lowermost position A and arm 103 cannot make contact with member 105. The position of cams 93 and 94 which are secured by screws to disc 92 can be changed to produce different weaving patterns. In the position shown, the pattern is changed twice after a different number of picks. By changing the angular position of the cams on the circumference of the disc, the number of picks after which shedding is changed can be changed. Instead of two cams, one only, or more than two, may be employed for producing a desired weaving pattern.

In addition to the aforescribed means responsive to a predetermined number of consecutive weft insertions for actuating the switching means, loom drive control means are provided which are responsive to the operation of the switching means and stop the loom when the switching means are in operation and re-start the loom at a predetermined moment of the switching operation, i. e. when said operation is substantially completed.

For automatically stopping the loom during switching from one binding to the other, a cam 87 is provided on a shaft carrying a sprocket wheel which is rotated by chain 43 at the same speed as clutch 41, 44. A cam follower 88 actuated by cam 87 reciprocates a rod 89 which is connected by a lost-motion means 90 with lever 31 actuating clutch 22. Because, after engagement of clutch 41, 44, cam 87 has been rotated through an angle $\alpha=60^\circ$ into the position shown in Fig. 6, cam follower 88 has pulled rod 89 and the lower part of lever 31 to the left, disengaging clutch 22 until cam 87 has been further rotated through about 270° . Thereupon lever 31 is moved counterclockwise by spring 31', and clutch 22 is engaged. In the meantime, shaft 45 has been rotated to

effect swinging of lever 72 to switch the roller holding levers 68, 69 from one set of cams for actuating the harness to the other, so that the loom, upon engagement of clutch 22, is started with the heddle frames in a position for the new binding.

Figs. 8 and 9 illustrate a modified device according to the invention. It has two parallel shafts 132, 133, each shaft axially movably but not rotatably, supporting a cam member provided with two sets of cam elements. The illustrated device is built for actuating four heddle frames and has four cam follower roller support levers 135 which are swingably supported by a shaft 134. Each lever 135 carries two rollers 136, each roller following a cam of a pair of cams forming a cam element. If lever 135 is in its left position, which is shown in Figs. 8 and 9, its rollers engage a cam element of a cam set on shaft 132 and if lever 135 is in its right position, its rollers follow the cams of an element of a set of cams on shaft 133. Levers 135 swing on a shaft 134 which is supported by two one-arm levers 137 to one of which handle 138 is pivoted. It has two notches adapted to be engaged by the wall of housing 34 for holding the handle and thereby blocking levers 137 and 135 in their extreme positions. Handle 138 is lifted against the pressure of a spring 139 to disengage it from housing 34. A rod 46 is pivoted to an extension at one end of each lever 135, as in Fig. 1, for transmitting the movement of the lever to a heddle frame.

As seen in Fig. 9, each cam member consists of 35 a cam drum, 111 for cam elements 140, 141 forming one cam set and cam elements 140', 141' forming another set of cam elements. Drum 112 comprises cam elements 142, 143 forming a third cam set and elements 142', 143' forming a fourth cam set. Shaft 133 is rotated by chain 35 and drives shaft 132 through spur gears 144 to 147. Cam drum 111 can be axially displaced by operating a lever 122 and drum 112 by operating a lever 122' so that either a cam element 140, 141 or 140', 141' on shaft 132 or a cam element 142, 143 or 142', 143' on shaft 133, depending on the position of levers 135, is actuating a heddle frame.

Though the drums 111, 112 are short and each has only two sets of cams, four different weaving patterns can be produced. The number of sets of cams on each drum can be increased to produce more weaving patterns.

The individual cam elements of different sets on one shaft are interspersed so that elements of different sets but intended for actuating the same heddle frame are axially juxtaposed and form groups, the sequence of the cam elements belonging to different sets being the same in each group.

Axial displacement of drums 111 and 112 must be effected when levers 137 and 135 are in neutral position between their two extreme positions.

Shafts 132 and 133 are driven by a main shaft 23 (Fig. 1) through a chain 35. If the cam sets 140, 141 and 140', 141' must rotate at a speed different from that of cam sets 142, 143 and 142', 143' for producing a desired binding, a speed reduction gear 144 to 147 must be provided. It comprises a wheel 145 whose diameter is one-half of that of wheel 144. Wheels 146 and 147 have like diameters. The shaft for the two wheels 145 and 146 is mounted on a crank 148 whose position can be changed if wheels 145 and 146 are replaced by wheels of different diameters for producing a different speed ratio between shafts 132 and 133.

Fig. 10 diagrammatically shows a fabric pattern in which four warp threads, *n*, *r*, *s*, *u*, are moved differently, necessitating the provision of four heddle frames and four roller levers 135 as shown in Fig. 9. The binding rule changes after insertion of weft threads *v*, *w*, *x*, *y*. As seen in Fig. 11, the weft threads at the left side of the fabric are bound by the warp threads according to the rule 1:1; after insertion of weft thread *v* and until insertion of weft thread *w*, the binding rule changes to 2:2, from weft thread *w* to weft thread *x*, the binding rule alternates between 3:1 for the warp threads *n*, *s*, and 1:3 for the warp threads *r*, *u*, whereby the new rule begins at different weft threads, producing a hollow weave whose two layers are individually bound according to rule 1:1. After weft thread *x*, a single layer weave begins following the rule 3:1, and, after weft thread *y*, the weaving pattern is the same as at the left side of the fabric.

Instead of switching the position of the members carrying the cam follower rollers, as members 72 in Fig. 2, the cam elements may be moved by moving shafts 39, 40 in Fig. 2 or shafts 132, 133 in Figs. 8 and 9, and the shafts 70 or 134 may be arranged to be stationary. This modification can easily be made by a man skilled in the art and is therefore not illustrated.

In the modification shown in Fig. 12, the heddle frame actuating rod 46 is pivoted to one end of a lever 151 which swings about a stationary pin 152. Lever 151 carries two rollers 153, 154, each roller following a cam of cam element 156. Six different cam sets 156 to 161 are provided, each set being made fast on a shaft 155. The six shafts 155 are mounted on a frame 163 which rotates on shaft 162. The main shaft 23 (Fig. 1) of the loom drives chain 35 which is laid around a sprocket wheel 164. The latter is on a shaft on which a second sprocket wheel is mounted which drives a sprocket wheel 166 by means of a chain 165. Wheel 166 is mounted on a sleeve which is rotatable on shaft 162. Six additional sprocket wheels 167 are made fast on said sleeve. Each wheel 167 drives one of six sprocket wheels 156' to 161'. Six chains 168 are provided for this purpose. Each of wheels 156' to 161' is coaxial with and made fast on one of the cam sets 156 to 161. Sprocket wheels 157', 159', and 161' have the same diameter as the wheels 167 and rotate at the same speed. The diameter of sprocket wheels 158' and 160' is greater than that of the wheels 167 to produce the speed reduction needed for a desired weave pattern.

Cam sets 156 to 161 are driven continuously during normal weaving, rotation of drum or frame 163 being prevented by inserting a latch 172 into one of six notches 173. If a different set of cams must be made to engage the roller lever 151, latch 172 is withdrawn from its notch against the action of spring 176, either by manipulating lever 174 or by energizing solenoid 175. Drum 163 is provided with a coaxial sprocket wheel 179 which is driven by chain 178 looped around wheel 179 and a sprocket wheel 177. The latter is driven by shaft 42 upon engagement of clutch 41, 44 because of withdrawal of pawl 71 (see also Figs. 1 and 6). The diameter of wheel 179 is six times as great as that of wheel 177, so that drum 162 rotates through 60° at one revolution of clutch 41, 44 and another set of cam discs is brought into engagement with roller lever 151, whereupon the drum can be locked again by means of latch 172. The device can be operated

by a control disc 92 as shown in Fig. 6, in which case the solenoid for actuating pawl 71 is electrically arranged in parallel with solenoid 175.

The chain drive of the cam discs 156 to 161 may be replaced by toothed gears by one skilled in the art and any desired rotational speed of the cam discs can be obtained by proper choice of the diameters of the sprocket wheels or gear wheels.

10 Two or more sets of cams may be arranged on each shaft 155, and drum 163 may be axially displaceable on shaft 162.

If the cam sets of consecutive bindings are arranged on different shafts 155, the cam sets can be moved into a position in which they can be engaged by the follower rollers 153 and 154, before the binding is changed.

15 The illustrated cam follower rollers may be replaced by pins or thumbs connected with levers 20 and cooperating with suitable guides without departing from the scope of the present invention.

The arrangement may be made so as to afford switching of the actuation instead of all of only 25 some of the heddle frames in a loom, the other heddle frames always being actuated in the same manner for the same binding. Two or more groups of cam-actuated members may be provided which are controlled differently, wherefore, 30 for example in Fig. 2, a fork lever 72 is provided for each group, each fork lever being actuated by an individual control disc 92 (Fig. 6).

Fig. 13 is a diagrammatic plan view of a mechanism per Fig. 12 in which the frame 163 carrying several cam sets can be axially displaced on shaft 162. A lever 180 is provided for this purpose which is fulcrumed on a stationary part 181 forming also a bearing for shaft 162. Lever 180 can be arrested in two extreme positions by a pin 183 inserted in a hole in the lever and into one of two holes in an arm 182 extending from part 181. Lever 180 is connected with shaft 162 by a pin extending from the lever into an annular groove in the shaft. Since each shaft 155 carries only two cam sets, shaft 162 need be arrested in only two different positions. The drum supporting sprocket wheels 166 is rotatable on shaft 162 and is driven by a chain 35 as shown in Fig. 12. Shaft 162 and with it frame 163 is rotated 50 by spur gear wheels 177, 179 in Fig. 12 for moving the several cam sets to active position. The frame can be arrested in the desired position by the means shown in Fig. 12. The cam follower rollers 153, 154 for actuating the harnesses by means of rods 46 are all supported by a shaft 152 which is supported by levers 185. The cam followers can be disengaged from their cams by swinging levers 185, see also Fig. 15.

60 In the modification of the device shown in Fig. 14, the cam sets can be displaced axially on their shafts 155. For this purpose, a lever 186 is provided for each cam set which lever has an end pivoted to frame 163 and a pin 188 extending into an annular groove 189 of the drum supporting the cam set. Each lever can be selectively arrested in two extreme positions by inserting a pin 187 through one of two holes in the lever into a cavity in the frame 163.

While I believe the above described embodiments of my invention to be preferred embodiments, I wish it to be understood that I do not desire to be limited to the exact details of design and construction shown and described, for

obvious modifications will occur to a person skilled in the art.

What is claimed is:

1. A mechanism for actuating the heddle frames in looms for weaving comprising at least two parallel shafts, at least one set of cam elements supported by each shaft, the number of cam elements in each set corresponding to the number of heddle frames required to produce a desired weaving pattern and the number of sets of cam elements corresponding to the number of different bindings required to produce the desired weaving pattern, cam follower means corresponding in number to the number of cam elements in one of said sets, individual actuating means individually interconnecting said follower means and the heddle frames, the configuration of the individual cam elements being such as to produce the movements of the individual heddle frames required for producing the desired weaving pattern, and switching means for changing the relative positions of said sets of cam elements and of said follower means for selectively engaging the latter by the former.

2. A mechanism as defined in claim 1, comprising swingable support means for said follower means, the latter being positioned between said parallel shafts, and said switching means being connected with said support means for swinging the latter to afford engagement of said follower means with either a set of cam elements on one of said shafts or a set of cam elements on the other shaft.

3. A mechanism for actuating the heddle frames in looms for weaving comprising two parallel shafts, a set of cam elements supported by each shaft, a heddle frame actuating means individually connected with each heddle frame and individually comprising cam follower means; each of said actuating means comprising a lever having a fulcrum disposed between said shafts, said lever supporting the respective follower means, and a rod pivotally connected with said lever; means for laterally displacing the fulcrum of said lever to afford engagement of said follower means either with a cam element on one of said shafts or with a cam element on the other shaft; the pivot axis of the pivotal connection of said lever and of said rod coinciding with the line of intersection of two imaginary planes extending through the axis of the fulcrum of said lever and through the middle between the points at which said follower means engage different cam elements, one of said planes corresponding to one extreme position of said fulcrum and the other plane corresponding to the other extreme position of said fulcrum when said cam elements are in positions corresponding to the position of the heddle frame actuated thereby in which the shed is in its middle position.

4. A mechanism for actuating the heddle frames in looms for weaving comprising at least two parallel shafts, at least two sets of cam elements axially displaceably supported by each shaft, the number of cam elements in each set corresponding to the number of heddle frames required to produce a desired weaving pattern and the number of sets of cam elements corresponding to the number of different bindings required to produce the desired weaving pattern, cam follower means corresponding in number to the number of cam elements in one of said sets, individual actuating means individually interconnecting said follower means and the heddle frames, the configuration of the individual cam

elements being such as to produce the movements of the individual heddle frames required for producing the desired weaving pattern, and means for individually axially moving said sets of cam elements for selective engagement of said sets with said follower means.

5. A mechanism for actuating the heddle frames in looms for weaving comprising at least two parallel shafts, at least one set of cam elements supported by each shaft, the number of cam elements in each set corresponding to the number of heddle frames required to produce a desired weaving pattern and the number of sets of cam elements corresponding to the number of different bindings required to produce the desired weaving pattern, cam follower means corresponding in number to the number of cam elements in one of said sets, individual actuating means individually interconnecting said follower means and the heddle frames, the configuration of the individual cam elements being such as to produce the movements of the individual heddle frames required for producing the desired weaving pattern, and a revolvable frame supporting said shafts parallel to the rotation axis of the frame, selective engagement of individual sets of cam elements with said follower means being effected by revolving said frame.

6. A mechanism for actuating the heddle frames in looms for weaving comprising at least two parallel shafts, at least two sets of cam elements axially displaceably supported by each shaft, the number of cam elements in each set corresponding to the number of heddle frames required to produce a desired weaving pattern and the number of sets of cam elements corresponding to the number of different bindings required to produce the desired weaving pattern, cam follower means corresponding in number to the number of cam elements in one of said sets, individual actuating means individually interconnecting said follower means and the heddle frames, the configuration of the individual cam elements being such as to produce the movements of the individual heddle frames required for producing the desired weaving pattern, a revolvable frame supporting said shafts parallel to the rotation axis of the frame, and displacing means individually connected with said frame and with said sets of cam elements for axially moving said sets, selective engagement of individual sets of cam elements with said follower means being effected by revolving said frame and by actuating said displacing means.

7. A mechanism for actuating the heddle frames in looms for weaving comprising at least two parallel shafts, at least two sets of cam elements axially displaceably supported by each shaft, the number of cam elements in each set corresponding to the number of heddle frames required to produce a desired weaving pattern and the number of sets of cam elements corresponding to the number of different bindings required to produce the desired weaving pattern, cam follower means corresponding in number to the number of cam elements in one of said sets, individual actuating means individually interconnecting said follower means and the heddle frames, the configuration of the individual cam elements being such as to produce the movements of the individual heddle frames required for producing the desired weaving pattern, and means for individually axially moving said sets of cam elements for selective engagement of said sets with said follower means, the individual cam ele-

ments of different sets on one shaft being interspersed and elements of different sets but intended for actuating the same heddle frame being axially juxtaposed and forming groups, the sequence of the cam elements belonging to different sets being the same in each group.

8. A mechanism for actuating the heddle frames in looms for weaving comprising at least two parallel shafts, at least one set of cam elements supported by each shaft, the number of cam elements in each set corresponding to the number of heddle frames required to produce a desired weaving pattern and the number of sets of cam elements corresponding to the number of different bindings required to produce the desired weaving pattern, cam follower means corresponding in number to the number of cam elements in one of said sets, individual actuating means individually interconnecting said follower means and the heddle frames, the configuration of the individual cam elements being such as to produce the movements of the individual heddle frames required for producing the desired weaving pattern, switching means for changing the relative positions of said sets of cam elements and of said follower means for selectively engaging the latter by the former, and drive means for rotating said shafts, said drive means comprising speed changing means for driving different shafts at different speeds.

9. A mechanism for actuating the heddle frames in looms for weaving comprising two parallel shafts, at least one set of cam elements supported by each shaft, the number of cam elements in each set corresponding to the number of heddle frames required to produce a desired weaving pattern and the number of sets of cam elements corresponding to the number of different bindings required to produce the desired weaving pattern, cam follower means corresponding in number to the number of cam elements in one of said sets, individual actuating means individually interconnecting said follower means and the heddle frames, the configuration of the individual cam elements being such as to produce the movements of the individual heddle frames required for producing the desired weaving pattern, said follower means being disposed between said shafts and individually comprising a two-arm lever, two cam follower rollers supported by each arm of said lever, displaceable pivot means swingably supporting said lever, and means for displacing said pivot means for selectively engaging the rollers on different arms of said lever with cam elements on one of said shafts or with cam elements on the other shaft.

10. A mechanism for actuating the heddle frames in looms for weaving comprising at least two parallel shafts, at least one set of cam elements supported by each shaft, the number of cam elements in each set corresponding to the number of heddle frames required to produce a desired weaving pattern and the number of sets of cam elements corresponding to the number of different bindings required to produce the desired weaving pattern, cam follower means corresponding in number to the number of cam elements in one of said sets, individual actuating means individually interconnecting said follower means and the heddle frames, the configuration of the individual cam elements being such as to produce the movements of the individual heddle frames required for producing the desired weaving pattern, switching means for changing the relative positions of said sets of cam elements and

of said follower means for selectively engaging the latter by the former, and means responsive to a predetermined number of consecutive weft insertions and connected with said switching means for actuating same.

11. A mechanism according to claim 10, comprising loom stop means connected with said switching means for stopping the loom when said switching means are in operation.

10. 12. A mechanism according to claim 10, comprising loom drive control means connected with and responsive to the operation of said switching means.

13. A mechanism for actuating the heddle frames in looms for weaving comprising at least two parallel shafts, at least one set of cam elements supported by each shaft, the number of cam elements in each set corresponding to the number of heddle frames required to produce a desired weaving pattern and the number of sets of cam elements corresponding to the number of different bindings required to produce the desired weaving pattern, cam follower means corresponding in number to the number of cam elements in one of said sets, individual actuating means individually interconnecting said follower means and the heddle frames, the configuration of the individual cam elements being such as to produce the movements of the individual heddle frames required for producing the desired weaving pattern, and switching means for changing the relative positions of said sets of cam elements and of said follower means for selectively engaging the latter by the former, said switching means comprising blocking means blocking the relative position of said sets of cam elements and of said follower means when they are in engagement.

14. A mechanism for actuating the heddle frames in looms for weaving comprising at least two parallel shafts, at least one set of cam elements supported by each shaft, the number of cam elements in each set corresponding to the number of heddle frames required to produce a desired weaving pattern, cam follower means corresponding in number to the number of cam elements in one of said sets, individual actuating means individually interconnecting said follower means and the heddle frames, the configuration of the individual cam elements being such as to produce the movements of the individual heddle frames required for producing the desired weaving pattern, switching means for changing the relative positions of said sets of cam elements and of said follower means for selectively engaging the latter by the former, and loom stop means connected with said switching means for stopping the loom when said switching means are in operation.

15. A mechanism for actuating the heddle frames in looms for weaving comprising at least two parallel shafts, at least one set of cam elements supported by each shaft, the number of cam elements in each set corresponding to the number of heddle frames required to produce a desired weaving pattern and the number of sets of cam elements corresponding to the number of different bindings required to produce the desired weaving pattern, cam follower means corresponding in number to the number of cam elements in one of said sets, individual actuating means individually interconnecting said follower

15

means and the heddle frames, the configuration of the individual cam elements being such as to produce the movements of the individual heddle frames required for producing the desired weaving pattern, switching means for changing the relative positions of said sets of cam elements and of said follower means for selectively engaging the latter by the former, and loom drive control means connected with and responsive to the operation of said switching means.

16. A mechanism for actuating the heddle frames in looms for weaving comprising at least two parallel shafts, at least one set of cam elements supported by each shaft, the number of cam elements in each set corresponding to the number of heddle frames required to produce a desired weaving pattern and the number of sets of cam elements corresponding to the number of

16

different bindings required to produce the desired weaving pattern, cam follower means corresponding in number to the number of cam elements in one of said sets, individual actuating means

5 individually interconnecting said follower means and the heddle frames, the configuration of the individual cam elements being such as to produce the movements of the individual heddle frames required for producing the desired weaving pattern, an axially displaceable revolvable frame supporting said shafts parallel to the rotation axis of the frame, and displacing means connected with said frame, selective engagement of individual sets of cam elements with said follower 10 means being effected by revolving said frame and by actuating said displacing means.
